UNITED STATES PATENT OFFICE.

WILLIAM H. MINER, OF CHICAGO, ILLINOIS.

DRAFT-RIGGING FOR CARS.

SPECIFICATION forming part of Letters Patent No. 461,443, dated October 20, 1891.

Application filed March 6, 1891. Serial No. 383,980. (No model.)

To all whom it may concern:

Be it known that I WILLIAM H. MINER, a citizen of the United States, residing in Chicago, in the county of Cook and State of Illinois, have invented a new and useful Improvement in Draft-Riggings for Railway-Cars, of which the following is a specification.

My invention relates to improvements in draft-rigging for railway freight-cars.

In the practical construction of cars it is essential that the draw-bar be connected against both pulling and buffing strains to the draft-timbers through a spring or springs in order to provide a gradual or cushioned absorption and transmission of strains and shocks to the body of the car, that the extent of this spring motion of the draw-bar should be only about two inches, and that the draft-timbers should be placed astride the draw-bar and its springs and as closely together as practicable. The above conditions and the reasons therefor are well known to those skilled in the art. Difficulty has, however, heretofore been experienced in so constructing the draft-rigging that it will withstand the enormous strains to which it is subjected, and at the same time properly cushion, absorb, and transmit the strains and shocks to the body of the car.

The object of my invention is to provide a draft-rigging of a simple, strong, and efficient construction, embodying great buffing and pulling resistance, and providing for a gradual or cushioned absorption and transmission of strains and shocks to the body of the car.

To this end my invention consists in a draw-bar having springs arranged tandem between the draw-timbers and through which the strains and shocks, either pulling or buffing, are gradually absorbed and transmitted to the draft-timbers.

It further consists in the combination of the draw-bar and draft-timbers with graduated springs arranged tandem.

It further consists in the novel devices and novel combinations of parts and devices herein shown and described, and more particularly pointed out in the claims.

In the accompanying drawings, which form a part of this specification, and in which similar letters of reference indicate like parts, Figure 1 is a plan view of a device embody-

ing my invention. Fig. 2 is a vertical longitudinal section on line 2 2 of Fig. 1. Fig. 3 is a cross-section on line 3 3 of Fig. 1. Fig. 4 55 is a horizontal section on line 4 4 of Fig. 2, and Fig. 5 is a detail perspective view of one of the stop devices.

In the drawings, A represents one of the cross-sills or frame-pieces of the car-body; B, 60 the draft-timbers, and C the draw-bar. Connected to the draw-bar C, preferably by a threaded nut c', is the draw-stem c, which passes through the coil-springs D d and D' d', the springs D d and D' d' being arranged 65 tandem or one behind or at the end of the other. The draw-bar C is further provided with a pocket C', secured thereto by gibbs c'', which fit in slots c', formed in the draw-bar, and also by a rivet or pin c', which passes 70 through the pocket C' and draw-bar C. The followers F F' for the springs D d fit within the pocket C'. F² F³ are the followers for the springs D' d'. G G' G² are the stops against which the several followers F F' F² F³ abut, 75 the intermediate stop G' serving both for the follower F' and the follower F². The stops are rigidly and firmly secured to the draft-timbers B by bolts g. They are further strengthened and held in place by lugs or projections 80 g', which project into suitable gains or recesses in the draft-timbers and through the metal strengthening-plates B', with which the draft-timbers B are lined on their inner faces. The metal plates B' are preferably from one- 85 fourth to three-eighths of an inch in thickness and about six inches in width, and serve not only to strengthen the draft-timbers at the place where they are weakened by the recesses b cut therein to receive the stops G G', but 90 they also serve to prevent the followers F F' from chafing the sides of the draft-timbers, as well as to distribute the strains equally to the various bolts g, which pass through the draft-timbers and stops, and also to afford a firm 95 support and bearing for the lugs g', with which the stops are furnished.

The re-enforcing plates B' need ordinarily only extend back as far as the cut-away portion b of the draft-timbers; but they may be 100 extended, if desired or required, back to the stop G², as indicated in dotted lines on Fig. 4 at b'.

K K are guide-plates for the followers F,

F', and F³. These guide-plates K are firmly and rigidly secured or bolted to the stops G, G', and G², and serve not only as guides for the followers, but also to secure all the stops rigidly and firmly together, and thus to strengthen and support the same individually. These guide-plates K thus serve to distribute the shocks or strains communicated to one stop by a follower to all the other stops, so that they all mutually coact together to resist the shock or strain and transmit it to the draft-timbers.

The flanged or chambered portion g³ of the middle stops G' G' serve as a guide for the follower F². The rear stop G² is or may be reinforced against buffing shocks or strains by the block or timber B², secured between the draft-timbers B B.

The pocket C' preferably consists of a wrought-iron bar about five inches wide by one and one-eighth inches thick, bent into a loop form, as is clearly shown in Fig. 2. The coiled spring D is preferably composed of a one and one-fourth inch crucible steel rod coiled six and one-fourth inches outside diameter and eight inches long and having two inches motion or compression. The inner coil d is preferably made of thirteen-sixteenths inch diameter crucible steel coiled three and five-eighths inches outside diameter and seven inches long and having two inches motion. The coiled spring D' is preferably made of one and one-fourth inch crucible steel rod, coiled six and one-fourth inches outside diameter, seven inches long and having two inches motion, and the smaller inside coiled spring d' is preferably made of one and thirteen-sixteenths inch crucible steel rod coiled three and five-eighths inches outside diameter and eight inches long and having two inches motion. When thus constructed, the graduated springs D d and D' d' will give an initial spring-resistance to either buffing or pulling strains of about twenty-three thousand pounds at each end of the car, which will be re-enforced after one inch of the spring motion is exhausted to about forty-six thousand pounds at each end of the car, making the complete capacity of spring-resistance ninety-two thousand pounds per car.

I prefer to construct the shorter springs d and D' of each pair as above described in relation to their relative length and extent of motion or compression, so that these two shorter springs may not become solid when the two longer springs D d' have become solid or been compressed to their fullest extent; but in this regard the extent of compression of the shorter springs may be varied without departing from my invention.

By thus combining the graduated springs D d and D' d', arranged tandem, with the draw-bar, the followers, stops, and draft-timbers I produce a practical device for absorbing and withstanding both light and heavy shocks to the cars, whether they be pulling or buffing shocks, and at the same time the

draft-rigging is given such strength that it is rendered practically impossible to injure the draft-rigging without wrecking the car. It should also be observed that by my invention the graduated spring-resistance itself greatly reduces the liability of breakage or injury to any part of the draft-rigging. By the tandem arrangement of the graduated springs the draft-timbers B B are brought close together and adjacent to the draw-bar which fits between them, so that in this respect my draft-rigging is equally strong as though only a single pair of springs were employed. By my tandem arrangement of the two pairs of graduated springs D d and D' d' and their combination with their followers and stops each pair of graduated springs D d or D' d', considered each pair as a whole, is made to act simultaneously with the other, the same as though the two pairs were arranged in parallel, so that although the springs are arranged in tandem the total amount of compression or spring motion is no more than it would be if they were arranged parallel, and at the same time by this tandem arrangement and combination of the graduated springs I am enabled to cause the heavy spring D of one pair to act simultaneously with the light spring d' of the other pair, whereas if the two pairs of springs D d and D' d' were arranged in parallel instead of tandem the two heavy springs must be made to act simultaneously with each other. The great advantage, however, of this tandem arrangement of the springs in their combination with the draw-bar and draft-timbers is that it enables the draft-timbers to be brought closely adjacent to the draw-bar, a condition absolutely requisite to the strength of the draft-rigging as an entirety. By the tandem arrangement of the springs also, I avoid all tendency to bind or tilt the followers by the unequal action of the springs as occurs where the springs are arranged in parallel.

Between the end of the pocket C' and follower F², I insert a washer c⁵ to take up the space and enable the bearing ends or shoulders of the intermediate stop G' against which the followers F' and F² abut to be farther separated or apart.

The follower F² may preferably have shoulders f to fit the guide-flanges g⁴ of the intermediate stop G'; but these gains or shoulders may be omitted, if desired, as may also the guide-flanges g⁴, in which case the guide-plates K would serve as guides for the follower F² the same as they do for the other followers F F' F³. This will be clearly understood from Fig. 3. Surrounding the draw-stem c I provide the usual guide-sleeves e⁶ for the springs d and d'.

To brace the draft-timbers B and hold them rigidly in proper relation to each other, I provide transverse brace-plates B³, which are or may be secured to the draft-timbers by the same bolts b², which attach the draft-timbers B to the longitudinal beams or timbers A' of the car-body.

The re-enforcing plates B' have or should have bent ends b³ to give them additional bearing against the stops.

I claim—

- 5 1. In a draft-rigging for railway-cars, the combination, with the draft-timbers, of a draw-bar and spring-arranged tandem for absorbing and transferring the pulling and buffing strains or shocks from the draw-bar
- 10 to the draft-timbers, a pocket secured to said draw-bar and surrounding one of said springs, and a draw-stem extending through both said springs and likewise secured to the draw-bar, followers, and stops, said followers and
- 15 stops being at each end of both said springs for conjointly compressing both said tandem-springs by either a pulling or buffing strain, substantially as set forth.
- 20 2. In a draft-rigging for railway-cars, the combination, with the draft-timbers provided with stops, of a draw-bar provided with a pocket, and a draw-stem secured thereto, stops and followers, and graduated springs arranged tandem for conjointly absorbing and
- 25 transferring either pulling or buffing strains or shocks from the draw-bar to the draft-timbers, said stops and followers being arranged at each end of both said tandem springs and said pocket surrounding one pair of said
- 30 graduated springs, substantially as specified.
3. In a draft-rigging for railway-cars, the combination, with the draft-timbers provided with stops, of a draw-bar provided with a pocket and draw-stem and two pairs of graduated springs D d and D' d', arranged tandem and operating conjointly under either pulling or buffing strains, substantially as specified.
- 35 4. In a draft-rigging for railway-cars, the combination, with the draft-timbers, of a draw-bar and two pairs of graduated springs D d and D' d', arranged tandem, the heavy spring of one pair acting simultaneously with the light spring of the other pair under either pulling or buffing strains, substantially as
- 40 specified.
- 45 5. The combination of draft-timbers B, having stops G, G', and G² secured thereto, of a draw-bar C, followers F F' F² F³, adapted to abut against said stops, a coiled spring between said followers F F', and another coiled
- 50 spring between said followers F² F³, substantially as specified.

6. The combination of draft-timbers B, having stops G, G', and G² secured thereto, of a draw-bar C, followers F F' F² F³, adapted to 55 abut against said stops, a pair of graduated springs D d between said followers F F', and a pair of graduated coiled springs D' d' between said followers F² F³, substantially as specified.

7. The combination of draft-timbers B, having stops G, G', and G² secured thereto, of a draw-bar C, followers F F' F² F³, adapted to abut against said stops, a pair of graduated springs D d between said followers F F', and 65 a pair of graduated coiled springs D' d' between said followers F² F³, said springs D d' being longer than said springs d D', substantially as specified.

8. The combination, with draft-timbers B, 70 having re-enforcing metal plates B' secured thereto on their inner faces, of stops secured to said draft-timbers, a draw-bar, spring, and followers, said stops having lugs or projections projecting through said re-enforcing 75 plates B', substantially as specified.

9. The combination, with draft-timbers B, having stops G, G', and G² secured thereto, of guide-plates K, secured to said stops, draw-bar C, followers F F' F² F³, and springs D d 80 and D' d', arranged tandem, substantially as specified.

10. The combination of draft-timbers B, having re-enforcing plates B', stops G, G', and G², furnished with lugs or projections g', 85 guide-plates K, secured to said stops, draw-bar C, having draw-stem c, followers F F' F² F³, and graduated springs D d and D' d', substantially as specified.

11. The combination of draft-timbers B, 90 having re-enforcing plates B', stops G, G', and G², furnished with lugs or projections g', guide-plates K, secured to said stops, draw-bar C, having draw-stem c, followers F F' F² F³, and graduated springs D d and D' d', said 95 stop G' having a chambered or flanged portion g⁴ to serve as a guide for said follower F², substantially as specified.

Dated at Chicago, February 14, 1891.

WILLIAM H. MINER.
